AUGUST HARTMANN, OF MONTCLAIR, NEW JERSEY, ASSIGNOR TO SPRATTS' PATENT, AMERICA, LIMITED, OF NEWARK, NEW JERSEY, A CORPORATION OF GREAT BRITAIN

EXHIBITION BENCH

Application filed July 27, 1928. Serial No. 295,634.

This invention relates to exhibition benches of the type used at dog shows and the like for displaying animals, and the object of the invention is to provide a bench for this purpose which is of simple, rugged construction and which may be readily set up and dismantled, the parts being capable of shipment in knock-down condition without being crated.

Exhibition benches and similar equipment used in animal shows are ordinarily not owned by the association or individual promoting the show but are supplied by the manufacturer who rents the material and sends his men to set it up in condition for use. At the conclusion of the show, the benches are dismantled and returned to the factory or sent to the city where the next show is to be held. As considerable equipment is required for a show and this equipment is subject to much handling and shipping, it should be of heavy rugged construction and of few parts.

Heretofore, the benches commonly used have included floor boards which are set on low wooden horses to lie a few inches above the floor of the exhibition room. These floor boards are wide enough for two rows of stalls or compartments separated by a back-board of suitable height, the stalls of each row being commonly defined by wire gratings which engage the back-board and have portions which pass through openings in the floor boards near the outer edges. The bench is then completed by a narrow skirting board along each outer edge of the floor boards in front of the gratings. As the back-board, skirting boards, and gratings rest somewhat loosely in place, it has been the practice to make the structure more rigid by using hook bolts which are passed through openings in the skirting boards, engaged with portions of the gratings, and then drawn tight to hold the gratings and skirting boards together. The gratings on opposite sides of the back-board then hold it in place and a reasonably rigid structure is secured.

This construction, however, is open to numerous objections, the principal ones being that much labor is involved in setting up the bench and setting and tightening the bolts.

Also the bolts are small and easily lost and

such loss not only represents a considerable item of expense for the bolts, but also may involve expensive delays while others are being procured. This objection is of great importance when it is considered that the size of the compartments on a bench and therefore the number of gratings used varies at the different shows and with the different types of animals to occupy the compartments, so that there must be kept on hand more gratings and bolts than are ordinarily in actual use to take care of emergencies. These additional bolts are also subject to loss and each time the equipment is shipped, the necessary bolts must be boxed and sent along with it.

This invention is accordingly directed to the provision of an exhibition bench of the type described which includes no bolts or fastening devices of that type, but is so constructed that the several parts interlock to produce a rigid structure. This structure is flexible in the respect that the width of the compartments may be varied as desired by the use of a greater or less number of gratings. The new bench includes no small parts which are likely to be lost in setting up, dismantling or shipping the equipment, and the labor charges for setting up and taking down the new bench are much lower than are incurred with a bench of the style heretofore in general use.

The new bench includes floor boards to be set on horses, a back-board, skirting boards, and a plurality of partitions, preferably in the form of gratings. The floor boards are provided with a row of apertures a short distance apart along each outer edge, and there are two such rows of apertures along the middle of the floor structure spaced apart so that the back-board may stand between these rows. Each grating is provided with a hook which extends over the top of the back-board, and with downward projections, one of which enters an aperture in one edge row in the floor. The skirting boards provided are of substantially greater thickness than those heretofore employed so that each board may stand solidly on edge, and each skirting board has apertures through it which may be placed in registry with those in the edge of the floor boards.

With this arrangement, the skirting boards are placed in position before the gratings are set, and the projection at the forward edge of each grating is then passed through aligned apertures in the skirting board and the floor board. When thus placed, the gratings are held rigidly in position and hold the back-board and skirting boards firmly and this result is accomplished without the use of bolts or other similar fastening devices. As will be apparent, the assembling and dismantling of the benches so constructed is a simple matter, requiring little labor, and there are no parts subject to loss.

For a better understanding of the invention, reference may be made to the accompanying drawings, in which

Fig. 1 is a view of the assembled bench in side elevation;

Fig. 2 is a plan view thereof;

Fig. 3 is a transverse sectional view showing one grating in place, and

Fig. 4 is a view of certain of the parts to illustrate the manner of assembling them.

Referring now to the drawings, the bench is shown as including a floor 10, which is supported on wooden horses 11, preferably collapsible so that they can be shipped flat. This floor is ordinarily made up of a plurality of matched boards of the desired length, for example, 15 feet, these boards being held together by cross cleats at the required intervals. If desired, the floor may be made up of two sections of boards hinged together along the median line so that the floor of a bench can be folded flat and have a width about one-half that of the complete bench.

The bench illustrated is of the customary double type, the floor being divided lengthwise by a back-board 12 made up of a plurality of matched boards secured together in any convenient manner. This back-board stands on edge along the middle line of the floor and runs from one end of the bench to the other. The compartments on each side of the back-board are defined by wire gratings 13, each grating preferably consisting of a bent rod 14, forming the top and front edge of the grating, a straight back rod 15 and a bottom rod 16, the square defined by these rods being completed by woven wire of the usual construction. Formed in the floor boards along the median line are two rows of apertures 17, the apertures in each row being spaced apart any desired distance, for instance 5 inches, and the rows spaced a sufficient distance to permit the back-board 12 to stand on edge between the rows.

The top rod 14 of each grating terminates at the rear in a hook 18 which may be placed to extend over the top of the back-board and downwardly along its opposite face a short distance. The rear rod 15 of each grating has a projection 19 which is adapted to pass through an aperture in one of the rows 17.

Along each outer edge of the floor is a row of apertures 20 in alignment with the apertures in the row 17 and spaced apart a similar distance. In the apertures of these outer rows are received the projecting ends 21 of the top and front rods 14 of the gratings.

The bench is completed by means of skirting boards 22 which are to be placed on the floor along each outer edge. Heretofore these skirting boards have been of relatively slight thickness and they have been held in place by having bolts inserted through openings through them, each bolt having a hook end to be engaged with a part of each grating. In the present construction the skirting boards 22 are made of increased width and each board is drilled from top to bottom as at 23 to form a plurality of apertures of the rows 20. The projecting end 21 of each grating may then be introduced through a hole 23 and into the corresponding hole 20 in the floor, and when the gratings are thus placed, they are held firmly in position and at the same time hold the skirting boards and back-board against displacement.

To provide a projection 21 of the desired length, it will be observed that the bottom rod 16 has an offset portion 24 which extends parallel to the vertical part of the front rod and engages this part of the rod at a distance from the end of the projection 21. The length of the projection is sufficient to pass through the skirting board and the floor board.

In setting up the new bench, the horses are first placed, then the floor board is placed in position and its sections opened so as to provide a floor of the ordinary width. The back-board is then laid flat on one section of the floor and the skirting board placed in upright position along the opposite edge of the floor with the holes in the skirting board registering with those in the floor.

One workman now raises the back-board to the desired upright position and holds it there, while another inserts the gratings in place. Each grating is raised above the floor and placed close enough to the back-board so that its hook 18 may pass over the top of the back-board. Then the grating is lowered so that the projection 19 enters one of the holes 17 and the forward projection 21 passes through the aligned openings in the skirting board and the floor board. This operation is repeated with each grating in that row and after a few such gratings have been placed, the back-board need no longer be held in position, and the workman who has been holding it can proceed to put gratings in place on the opposite side from that where gratings have been installed. When all of the gratings are in place, the back-board is held firmly in position between the rear upright rods of the gratings in the

two rows and each skirting board is held in place by the projections 21 of a plurality of gratings.

It will be observed that with this bench 5 no bolts are required and no similar small fastening means, which are readily lost or mislaid are used. The bench may be assembled in a few minutes without difficulty and as quickly taken down. The labor cost 10 for installing the benches necessary for a large show is, therefore, relatively unimportant and the owner of the benches incurs no loss by reason of the loss of bolts and similar parts. When the bench is dis- 15 mantled, the horses, floor board, back-board, skirting boards, and gratings may be shipped without crating and these parts are not subject to damage since they may be made of strong construction. By forming the 20 floor and skirting boards with a plurality of apertures in each row spaced apart a short distance, the gratings may be placed to form compartments of any suitable or desired width according to the use to which 25 the bench is to be put. The bench, therefore, is flexible in use, consists of only a few simple inexpensive parts, shipping charges for transporting it are low and the labor cost for assembling it and dismantling it 30 are much less than those incurred in connection with benches of the construction here- tofore employed.

What I claim is:

1. An exhibition bench comprising a 35 floor, a back-board resting on the floor at a distance from one edge thereof, a skirting board resting on the floor along said edge, and partition means to subdivide the floor into a row of exhibition spaces, these parti- 40 tion means having portions engaging the back-board and other portions passing through the skirting board and entering the floor.

2. An exhibition bench comprising a 45 floor having a row of apertures adjacent each edge, and a pair of rows of apertures on each side of the median line of the floor, a back-board resting on the floor between the 50 rows of apertures spaced inwardly from the edges of the floor, skirting boards resting on the floor, one along each edge, each skir- 55 ting board having a plurality of apertures adapted to be placed in registry with the floor apertures near each edge of the floor, and a plurality of partitions disposed on each side of the back-board on the floor, each partition having a part engaging the back- 60 board, and having spaced projections, one projection being insertable into a selected aperture of a row near the back-board, and the other aperture being insertable through a corresponding aperture in the skirting board and into the aperture in the floor in 65 registry therewith.

3. An exhibition bench comprising a

floor, a skirting board resting on the floor along one edge, and a grating mounted on the floor to extend at an angle to the skirting board, this grating having a part passing through the skirting board to hold it against 70 displacement.

4. An exhibition bench comprising a floor having a plurality of apertures along one edge, a skirting board resting on the floor along said edge and having a plurality of apertures adapted to be placed in registry with those in the floor, and a grating adapted to be placed upright on the floor at an angle to said edge, this grating having a part in- 75 sertable through any selected aperture in the skirting board and the registering aperture in the floor.

5. An exhibition bench comprising a floor having a plurality of apertures along one edge, a back-board resting on the floor at a 80 distance from this edge, a skirting board resting on the floor along said edge and having a plurality of apertures adapted to be placed in registry with those in the floor, and a grating adapted to be placed upright in the floor 85 at an angle to said edge, this grating having a part insertable through any selected aper- 90 ture in the skirting board and the registering aperture in the floor and also having a part engaging the back-board to hold it from dis- 95 placement from upright position.

6. A grating for use as a partition on an exhibition bench which comprises a bottom rod, a rear upright rod and a front upright 100 rod, said upright rods extending beyond the bottom rod which is connected thereto, and the bottom rod having a portion extending parallel to and spaced from the front rod to provide a projecting portion thereof of in- 105 creased length.

7. A grating for use as a partition on an exhibition bench which comprises a substan- 110 tially rectangular frame made up of metal rods with its center closed with woven wire, the said rods of the frame projecting beyond the bottom rod and the bottom rod having a portion extending parallel to one of said side rods and connected thereto at a point offset from the main portion of said bottom rod to provide a projecting portion on this side rod 115 of substantial length.

8. An exhibition bench comprising a floor, a back-board resting on the floor at a distance from one edge thereof, a skirting board rest- 120 ing on the floor along said edge, and a parti- 125 tion mounted on the floor and provided with means for holding the back-board against displacement, this partition having an exten- sion from its front edge passing through the skirting board and into the floor.

In testimony whereof I affix my signature.
AUGUST HARTMANN.
